TRANSMISSION OF PRINTER SIGNALS BY
RADIORichard E. Mathes, Westfield, N. J., assignor to
Radio Corporation of America, a corporation
of DelawareApplication September 15, 1932
Serial No. 633,257

6 Claims. (Cl. 178—52)

This invention relates to printing telegraphy, and is especially concerned with communication circuits for the transmission and reception of printer signals.

- 5 A primary object of the present invention is to provide a system capable of automatically re-laying, by radio or wire line, signals from start-stop printer mechanisms, such as stock ticker signals.
- 10 Another object is to obtain secrecy and accuracy of communication, and this is accomplished by a storage arrangement for automatically repeating each signal character at intervals a predetermined number of times.
- 15 A more specific object is to enable the transmission of the 8-unit code such as is used, for example, by the New York Stock Exchange ticker system, by means of a synchronized 6-unit code. The invention, however, is not limited in its use to 20 8-unit stock ticker signals, since it may readily be employed with code signals having any desired number of units, such as the 5-unit code which is in general use in systems employing printers of the well known Kleinschmidt or Teletype type.
- 25 A feature of the invention resides in the means employed for converting start-stop signals to a synchronized code for transmission, and subsequently reconverting the received synchronized signals back to start-stop characters.
- 30 Another feature resides in the control of the automatic tape transmitter from the synchronized multiplex apparatus.
- In a particular embodiment of this invention the printer signals are fed into a reperforating 35 device which functions to discard the start and stop signals received from the line and to convert the message characters into a tape record which in turn actuates an automatic tape transmitter under the control of a multiplex transmitter.
- 40 The latter may be of any desired type, but in the preferred arrangement, in order to avoid fortuitous distortion, such as may be due to line noise, cross talk, interference, static, or fading, it is one which provides for the repeated transmission of each unit character two or three times at intervals which are rather long compared with the length of the unit character. At the receiver these several repetitions are stored until the last one has been received. Then they are automatically compared and the distortions, which did not occur on all of the several repetitions are rejected, and the resulting clean signal is passed on to the retransposing or printing mechanism.
- 45 One advantage of such an arrangement is that it permits the transmission and ultimate reception of stock ticker or start-stop printer signals over circuits of approximately all types in which heavy distortion is apt to be encountered with a sufficiently high degree of accuracy to meet the de-
- sired strict requirements of communication systems.
- A modification of this invention utilizes an electrical contactor device in combination with suitable relay apparatus and a phase corrector in place of the mechanical tape reperforator. From this it will be evident that, if desired, the reperforator mechanism may readily be replaced by any other suitable electrical arrangement. 65
- The invention is described in more detail in the following description which is accompanied by drawings, wherein:
- Figure 1 illustrates, diagrammatically, one method of practicing the present invention; and 70 Figure 2 illustrates a modification thereof.
- Figure 3 shows, schematically, a suitable reperforator which may be employed for converting 8-unit code signals to 6-unit tape reperforated signals.
- Figure 3a shows in more detail the operation of the selector bar and magnet of the reperforator of Figure 3. 80
- Figure 3b is a modification of the apparatus of Figure 3 and illustrates the use of electrical contactors instead of the punch mechanism. 85
- Figure 4 illustrates, schematically, a multiplex transmitting and receiving system of the preferred type.
- Figure 5 shows a special distributor adapted to convert synchronized 6-unit signals into start-stop 8-unit characters; and 90
- Figure 6 shows a master distributing relay circuit for transmitting signals to a plurality of tickers.
- Referring to Figure 1, there is shown, by way of example only, one particular method, in accordance with the teachings of the present invention, of using a start-stop system with a synchronized multiplex transmitter for automatically re-laying printer signals. Stock ticker start-stop signals of the 8-unit type are received over the line L from the regular master ticker transmitter customarily used to transmit the stock ticker signals to the various receivers located in the different brokers' offices and fed into unit B, which may be any well known type of reperforator which is slightly modified to perforate the tape in the 6-unit code used by the ticker service. This reperforator, later described in more detail in connection with Figure 3, discards the start-stop pulses and records the actual message characters on tape 3 in 6-unit characters, which in turn is fed into automatic tape transmitter unit C. Perforated tape 3 is in the form of a slight loop and acts as a storage reservoir to equalize the various time intervals between the ticker signals and the automatic tape transmitter C. Such storage reservoir has been found necessary since there is no assurance that each letter combination will occur at a time 105
- 110
- 115
- 120

interval which is an integral number of units equal to the length of one letter, particularly so since the signal is to be impressed upon a multiplex system wherein each character must be compressed to a time length equal to the time of a distributor revolution divided by the number of sections or channels per revolution. This compression is effectively accomplished by the tape in conjunction with unit C.

10 Unit C is an automatic tape transmitter of any well known satisfactory type such, for example, as the Siemens automatic transmitter or any of those described by H. H. Harrison in his book on "Printing Telegraph Systems and Mechanisms" (1923), pages 172 to 187, except that those referred to are for the 5-unit tape, instead of for the 6-unit tape. Since the principles of construction and operation are the same, it is, of course, obvious to anyone skilled in the art that such a transmitter can just as readily be made up for 6-units as for 5 units.

From the automatic tape transmitter the signals are passed on to unit D which may be any type of multi-channel multiplex transmitter, but in the preferred embodiment is one which functions on the Verdan principle for the elimination of static or fading on radio circuits or for the elimination of other types of distortion on wire telegraph systems. The Verdan principle of signal character repetition is well known in the art and is adequately described in United States Patent No. 1,677,062, granted July 10, 1928, to C. Verdan and L. Loiseau. Multiplex unit D is a special type of multiplex channelling arrangement and consists essentially of two parts as described subsequently in connection with Figure 4: first, a standard multiplex distributor which provides several channels of the time division type; and secondly, a special distributor system associated with a signal storage system which functions to store up a portion of the transmitted signal for a period of time of the order of some 2 ± 1 seconds. At the end of that period these stored signals are returned to another channel of the multiplex transmitter and are again transmitted to the distant station. Present practice for Verdan systems seems to have standardized on the original transmission and two repetitions, though this limitation is by no means inherent, and the number of repetitions used may be chosen to meet the particular operating conditions. For present purposes the unit D should be modified to provide, say, three 6-unit channels on the multiplex distributor and a 6-unit storage system.

From unit D the signals go to control the communication circuit here designated "a", be it radio, carrier, or wire line. At the distant end these signals are received by well known methods and converted into direct current pulses which may be regenerated if desired.

The signals from the communication circuit are then passed into unit U which is a multiplex receiver of a type corresponding to unit D. In this case, however, all preceding transmissions are retained in the storage system until the last one has been received when they are automatically compared and only those units of the code character which have been perfectly received on all transmissions are passed on to the selecting relays of unit W. Unit characters not received on all transmissions, and which are the result of the fortuitous distortion which is inherently random, are rejected and are thus ineffective to set up the relays of unit W erroneously. Unit U

should also be modified for three 6-unit channels on the multiplex receiving distributor, and a 6-unit storage system.

The receiving signals are then passed on to a reperforator unit W which is an ordinary type of reperforator of a kind described by Harrison in his book "Printing Telegraph Systems and Mechanisms", on pages 212 to 217, except that it is modified to perforate the 6-unit tape. It is not necessary, however, that this unit operate from a start-stop signal since it may be arranged to operate from a cadence signal from unit U.

The perforated tape sent out by unit W controls another unit X which is an automatic tape transmitter modified for 6-unit tape and functions exactly as does unit C. In this case, however, the tape and auto combination are effective in lengthening the time duration of the character in order to fill in the interval previously used by the repetition channels and thus restore the 6-unit characters to the same length they had at the originating ticker transmitter.

A special distributor is now provided to supply the start pulse, pass the 6 units set up at the automatic transmitter, and supply the stop pulse, all successively, in a manner to be described later in more detail. This distributor is designated as unit Y and is driven at the same rotation speed as the multiplex distributor of unit U. By this operation there is reproduced the ticker or printer signal in exactly the form in which it first reached unit B from the stock ticker or printer transmitter. This signal may now be distributed to the receiving tickers which are of the standard recognized form.

Referring to Figure 2, there is shown a modification of the present invention wherein reperforator unit B is modified to provide an electrical contactor device instead of a perforating punch machine. These contacts, which are illustrated in Figure 3b, are connected to unit D in lieu of the contacts of the automatic tape transmitter. Such a system may be used if the originating transmitter is of the cadence type. In this case the start of each character is always a time interval later than the start of the preceding character, which interval is an integral multiple of the duration of a character. Therefore, the storage action of the tape is no longer necessary to smooth out unequal time intervals. The compression effect is obtained from the storage inherent in the relays of the reperforator.

Inasmuch as the modified system is now operating from a cadence type of transmitting system, it becomes necessary to consider the transmitter for purposes of speed and phase adjustment as a master station for the entire system, and for this purpose a phase and speed correction system is provided in unit E to maintain the multiplex transmitter commutators in speed and proper phase. This system, which functions to produce the proper correction from the signal elements, does not require the transmission of any sort of special correcting signal from the transmitting or originating station. Phase correction systems of this type are well known in the art and are adequately described, for example, by Harrison hereinabove referred to, on page 314, et seq.

Receiving multiplex unit U and special distributor unit Y are of a type similar to those previously described in connection with Figure 1. Unit F may comprise the output relay of a multiplex receiving system and will be described in more detail later. The tongues of these output

relays are arranged to be connected directly with the signaling segments of the special distributor unit Y.

In order to permit distribution to a multiplicity 5 of tickers and ticker loops, unit G has been provided as a heavy duty master relay system to be operated from the special distributor unit Y in a manner shown in Figure 6. It has been found that the distribution of the signals to the tickers 10 cannot be effectively accomplished directly from the distributor because of the large amount of power necessary to be handled for such distribution.

One major advantage of the system of Figure 2 15 resides in the elimination of the considerable delay inherent in the loops of reperforated tape. With such an arrangement the delay is reduced to a certain low minimum inherent in one character storage in units B and W and in the approximately 4 seconds delay inherent in the Verdan storage system.

In Figure 3 there is shown reperforator apparatus suitable for use in unit B. In this figure is shown a distributor commutator having a brush 25 arm 10 driven by a motor 11, the speed of which is controlled in accordance with well known practice in the printer art. The speed is so chosen that brush arm 10 will rotate at a speed slightly faster than that corresponding to the incoming 30 printer signals. The commutator has been provided with six signalling segments and, in addition, with a start-segment and a stop-segment to correspond with the eight units constituting a letter or character as produced by the transmitting system. Each signalling segment is assigned to an individual selector magnet a, b, c, d, e or f in such a manner that as brush arm 10 rotates in synchronism and phase with the transmitter the signalling units emanating therefrom will be routed to the various selector magnets 40 in succession and will cause these magnets to function, depending upon whether the unit signal received from the transmitter is positive or negative. If the signal is positive the corresponding selector magnet will attract the armature and in so doing will complete a self-locking circuit through the back contact of the restoring magnet M1 to a positive potential indicated in the drawings by a plus sign. As will be seen in 45 Figure 3a, this also causes the tip of the selector magnet armature to fall opposite the slot in the selector bar. Upon completion of the reception of the six signalling units the brush of the distributor then passes on to the stop segment which 50 supplies a positive potential from the receiving line relay through the brush arm and segment to the punching magnets, thus attracting all six selector bars. Those bars for which the selector magnets have not been actuated by the received 55 signalling elements are prevented by the magnet armatures from travelling toward the punch magnets and, therefore, do not actuate their punches. The other selector bars are permitted to travel toward the magnets and in so doing force their individual punches through the paper tape, thus producing perforations in the tape in accordance with the combinations of the six signalling units received from the distant transmitter. A special circuit utilizing a slow release- 60 quick operate magnet M3 is provided to close an auxiliary circuit to cause the reperforator to punch center holes only for a length of time equal to the loop between the reperforator punch and the auto pins. Relay M2 may, for example, be caused to operate on 5 second intervals.

Such an arrangement will not cause an unwarranted delay due to live punched tape being held in this loop when the ticker experiences a long pause. Other auxiliary circuits may be provided to feed such blank tape at a higher rate than live, punched sections. 80

As the brush arm continues its rotation it comes in contact with a short auxiliary segment set between the start and stop segments. This permits a positive potential to be applied from the receiving line relay through the brush arm and auxiliary segment to operate restoring magnet M1, thus opening the circuit through its back contact and releasing the armatures of selector magnets which are then returned to their normal position by their individual springs. At the same time a detent fastened to the brush arm comes in contact with the armature of detent magnet M2 and prevents the arm from further rotation. The arm is, of course, connected to the driving motor 11 by means of a friction drive, in the well known manner, to permit of its being stopped by the detent while the motor continues to run. Brush arm 10 will remain stopped as long as the stop unit persists in the receiving line relay in accordance with the signal received from the distant transmitter. However, as soon as the distant transmitter sends the start unit of the next succeeding character, the tongue of the receiving line relay will move from its positive to its negative potential contact and will thereby complete a circuit through the brush arm and a second auxiliary contact carried on an inner ring of the distributor to actuate detent magnet M2 which then attracts its armature 10 and permits the brush arm to again commence rotation. 100

It will thus be seen that brush 10 makes one rotation for each character received from the distant transmitter and will cease moving upon completion of one rotation unless and until the start of the next character is received from the distant transmitter. The result is the production of a reperforated tape bearing only the six signalling units which omits the start unit and 115 stop unit and also prevents the occurrence of false characters such as false spaces on the tape through delay at the transmitter in sending a succeeding character. 120

Obviously, many other circuit arrangements 125 may be used for the actual perforation, as well as other forms of distributors.

The tape thus produced by the reperforator of Figure 3 may then be fed into a six unit automatic tape transmitter with a loop of tape intervening 130 between these two units as required by physical design of the equipment. This automatic tape transmitter, which is designated as unit C in Figure 1, is under control of the multiplex transmitter and, as mentioned above, may be any well known type of equipment. 135

Figure 4 is a multi-channel multiplex telegraph transmitter which employs the Verdan principle for the elimination of static or other types of fortuitous distortion on telegraph systems. The particular system shown accomplishes the storage of signals through the medium of condensers instead of through mechanical means, and shows the connection for the first unit of a six unit character. The transmitting multiplex distributor is in accordance with standard practice for such transmitters and is provided with 20 segments. The first six constitute one channel; the following six a second channel; the next six a third channel and the remaining two are used 140 145 150

for the purpose of sending a correction signal which is utilized in the maintenance of phase between the receiving distributor and the transmitting distributor in accordance with any of the several methods well known to the art. Carried on the same shaft and geared to a lower speed is an auxiliary or transmitting storage commutator. The relationship between the two commutators is such that when the first unit of a character is set up in the automatic tape transmitter, positive or negative potential is applied through segment 1D, the brushes, and segments 1G and 1H to charge condensers C1 and C2. At the same time, this potential is applied through the brush of the storage commutator to segment 1A of the multiplex distributor from which it is passed through its brushes to the outgoing line relay 18. The effect of such action is that the signal unit set up at the tape transmitter has been transmitted to the line and, simultaneously, has been stored on condensers C1 and C2. At some later time, which is determined by the gearing ratio between the multiplex distributor and the storage commutator, brushes of the latter come in contact with segment 1E at the same time that the brushes of the multiplex distributor are in contact with 1B. This completes a circuit from condenser C1 through the above mentioned segments to the outgoing line relay 18 and permits the condenser to discharge therethrough, thus resulting in again transmitting this same unit to the line. After an equal interval of time, brushes of the storage commutator are in contact with segment 1F at the same time that brushes of the multiplex distributor are in contact with segment 1C, thus completing the circuit from C2 through these segments to the line relay 18 which permits the condenser to discharge and thus transmit to the line for the third time the unit as set up by the tape transmitter.

In this manner the first signal unit of a character is transmitted over the communication circuit. It will be understood, of course, that similar actions take place through segments 2A, 3A, 4A, 5A and 6A in succession, and that separate storage commutators and separate condensers are provided for each of these six units.

From the foregoing it will be seen that thus far signals have been received from start-stop printer transmitter mechanism and reduced to six units by omitting the start and stop pulses, that the tape has been perforated bearing these six units, that this tape has been analyzed and the six units transmitted through the multiplex transmitter to the outgoing circuit.

These signals are received by unit U which is the receiving equipment corresponding to the transmitting set up of unit D, also shown on Figure 4. The receiving multiplex distributor commutator, it will be noted, has the same arrangement of segments as the transmitting distributor, but the receiving storage commutator is arranged somewhat differently.

The incoming line relay 19 produces the signals as sent from the multiplex transmitter together with any additional signals due to fortuitous distortion. The contacts of relay 19 are arranged so that for negative signals, potential from the battery 20 will be applied through the relay to the brushes of the multiplex distributor. When the brush has come in contact with segment 1A the battery circuit will be completed through segment 1A, brushes of receiving storage commutator and segment 1D to charge the condenser C3. At some later time equal to the

time of delay at the transmitter, the distributor brush of the receiving distributor is in contact with segment 1B coincident with the receipt by the line relay 19 of the second transmission of the unit signal. This again completes the circuit through the relay and segments 1B and 1E to again charge condenser C3. After a further time interval the multiplex brush is in contact with segment 1C when the third transmission of the unit arrives at the incoming line relay. This again causes the circuit from the battery to be completed through segments 1C and 1F to again charge the condenser. However, at this same time the brush of the receiving storage commutator is also in contact with an auxiliary segment 1G which is connected through a relay 21 back to the opposite side of C3. This closure permits the discharge of C3 through the coils of the output relay 21 to actuate this relay in accordance with the polarity of the received signal unit. Now, if during any of these three transmissions distortion had been present and of sufficient amplitude to operate the incoming line relay 19, its tongue would have been on the upper contact instead of on the lower and, therefore, the condenser C3 would not have been charged. It is obvious that this condition could have existed during the contact of the brush with any two of the three segments 1D, 1E or 1F and still the relay would have been operated to negative by the discharge of the condenser C3. Herein resides the application of the Verdan principle. The signalling units are transmitted over the communication circuit as negative or no-current pulses and the spacing units are transmitted as positive or mark pulses. Consequently, distortion due to noise or static must produce at the receiver an action similar to that produced by the spacing signal at the tape transmitter.

If desired, the coils of the output relay 21 connected to condenser C3 may be replaced by a condenser arrangement. The reperforator and automatic transmitter at the receiving end only could then be omitted. Such an arrangement may consist of six condensers or relays for 6-unit code operation, which would be energized by the output from the mux receiver and thus caused to store pulses until they could be analyzed and passed to the output of the special distributor. An advantage of such arrangement resides in the simplification of the equipment and in the elimination of the delay inherent in the loop of tape between the reperforator and the automatic tape transmitter.

In Figure 5 is a special distributor corresponding to unit Y designed for the purpose of re-inserting the start-stop pulses before and after the receipt six signalling units of the character in order to permit the output circuit to operate the original start-loop recorder. This distributor is carried on the same shaft as are the commutators of the multiplex receiver or on a definitely associated or synchronized shaft. The gearing to the brush of this distributor is such that it will make one revolution for every revolution of the multiplex distributor. Six signalling segments are each connected to their respective contacts on the automatic tape transmitter unit. Positive potential is connected to the stop segment and negative potential is connected to the start segment. As the brush arm 13 revolves it will send a start pulse and then send the six signal units in accordance with the position of the contacts which in turn are de-

terminated by the reperforated tape. Upon completion of this the stop unit is transmitted. The result of this action, as will be evident, is to transmit the six units together with start and stop pulses in a regenerated form identical with the signals received by unit B from the start-stop transmitter.

If desired, instead of the perforation of holes in the tape one may substitute electrical contacts for the paper punches in a manner shown in Figure 3b. It should be obvious that this substitution will result in selection of plus or minus potentials by the selector bars. The contacts carried by the individual selector bars are then connected directly to the individual segments of the transmitter storage commutator. In other words, these contacts are substituted for the contacts of the automatic tape transmitter shown connected to the circuit of Figure 4.

As regards the operation of the apparatus in unit F in Figure 2, it is necessary that an auxiliary contact designated as Q in Figure 4 be included in the multiplex distributor. The distributor brush is arranged to come in contact with this segment just shortly before it starts to pass over segments 1C through 6C, and in conjunction with the storage commutator, passes the received signal to the six output relays. When it makes contact with segment Q, positive potential is supplied through this segment to a second winding on the output relay and thence back to minus and causes tongues of all output relays to be returned to their upper contacts. The position of the brush on the distributor, Figure 5, is so positioned that contact with its segment Q occurs when the special distributor brush is on the stop segment. The effect of this is to permit the operation of the output relays to take place at a time when the special distributor brush is not analyzing any of the six segments and, therefore, will not cause interference or errors with the output signal from the system.

Although the above description of a specific embodiment has been laid out to fit the stock ticker system used by the New York Stock Exchange and, therefore, is set up for a six unit code, it is obvious that the same principles may be applied to five unit start-stop systems of any sort and that the application of the scheme is not limited only to the transmission of stock quotations or similar matter, but may be used for the transmission of any type of matter normally handled by means of start-stop printer systems. Furthermore, any form of apparatus may be used which incorporates the Verdan principle of automatic repetition and storage, such apparatus utilizing, for example, storage in the form of pin drums or disks, steel tapes upon which signals are magnetically recorded, condenser banks, electro-magnetic relays, or any other type of means for storing signals for subsequent repetition.

In the interests of greater secrecy, one may, if desired, reassign differently the pins of the automatic tape transmitter, designated as C in Figure 1, to the segments of the transmitting multiplex distributor, and reciprocally reassign the segments of the receiving distributor to the magnets of the reperforator in a predetermined manner. Theoretically, there are about 720 possible arrangements of these contacts.

I claim:

1. In a printing telegraph system having start-

stop printer mechanism and synchronous apparatus for transmitting signals received from said start-stop mechanism, the method of transmission which comprises, translating start-stop printer signals into synchronous type of signals, transmitting each of the synchronous type of signals at predetermined intervals a plurality of times, receiving and storing said synchronous type of signals, and subsequently reconverting said synchronous type of signals into start-stop printer signals.

2. Printing telegraph apparatus having, in combination, printer mechanism for transmitting multiple unit code signals having start and stop pulses, a reperforator unit for receiving said multiple unit code signals, said reperforator being arranged to record the printer signals on tape and to discard said start and stop pulses, a synchronous multiplex transmitter, an automatic tape transmitter arranged to receive said tape and under control of said multiplex transmitter, a synchronous multiplex receiver, and means connected to said receiver for reinserting start-stop pulses into said multiple unit code signals.

3. Printing telegraph apparatus having, in combination, printer mechanism for transmitting multiple unit code signals having start and stop pulses, a reperforator unit for receiving said multiple unit code signals, said reperforator being arranged to record the printer signals on tape and to discard said start and stop pulses, a synchronous multiplex transmitter, an automatic tape transmitter arranged to receive said tape and under control of said multiplex transmitter, a synchronous multiplex receiver for receiving the signals transmitted by said multiplex transmitter, a reperforator connected to said receiver for recording said received signals on tape, an automatic tape transmitter arranged to receive said tape, and a special distributor connected to said automatic transmitter for reinserting start-stop pulses into said received signals.

4. Printing telegraph apparatus having, in combination, printer mechanism for transmitting multiple unit code signals having start and stop pulses, a storing device for discarding start-stop pulses, said storing device being arranged to record the printer signals on tape and to discard said start and stop pulses, a synchronous multiplex transmitter, an automatic tape transmitter arranged to receive said tape and under control of said multiplex transmitter, a synchronous multiplex receiver, and means connected to said receiver for reinserting start-stop pulses into said multiple unit code signals.

5. Printing telegraph apparatus having, in combination, printer mechanism for transmitting multiple unit code signals at a synchronous rate, a relay contactor device for receiving said multiple unit code signals, a transmitter arranged to receive the signals from said relay device and to transmit the signals over a communication circuit, phase and speed correction mechanism for controlling said transmitter, a receiver connected to said communication circuit, and means connected to said receiver for inserting start and stop pulses into said multiple unit code signals.

6. A printing telegraph arrangement as defined in claim 4 characterized in this, that said synchronous multiplex transmitter is arranged to transmit signals at predetermined intervals a plurality of times.

RICHARD E. MATTHES.

CERTIFICATE OF CORRECTION.

Patent No. 1,944,565.

January 23, 1934.

RICHARD E. MATHEIS.

It is hereby certified that error appears in the printed specification of the above numbered patent requiring correction as follows: Page 3, line 74, for "M2" read M3; page 4, line 136, for "start-loop" read start-stop; and page 5, line 106, claim 3, for "dischard" read discard; and that the said Letters Patent should be read with these corrections therein that the same may conform to the record of the case in the Patent Office.

Signed and sealed this 14th day of July, A. D. 1936.

Henry Van Arsdale

(Seal)

Acting Commissioner of Patents.
